CLAIM

The ornamental design for a battery, as shown and described.

DESCRIPTION

FIG. 1 is a perspective view of a new design for a battery; FIG. 2 is a front view thereof; FIG. 3 is a rear view thereof; FIG. 4 is a right side view thereof; FIG. 5 is a left side view thereof; FIG. 6 is a top view thereof; and, FIG. 7 is a bottom view thereof.

The broken lines in the drawings are for the purpose of illustrating portions of the battery that form no part of the claimed design.

(Continued)

The battery is shown with a symbolic break in its height. The appearance of any portion of the article between the break lines forms not part of the claimed design.
